UNITED STATES PATENT OFFICE.

CHRISTIAN W. WINTHORP, OF FRESNO, CALIFORNIA.

SPRING-LEAF SEPARATOR.

1,237,436.

Specification of Letters Patent. Patented Aug. 21, 1917.

Application filed June 22, 1916. Serial No. 105,151.

To all whom it may concern:

Be it known that I, CHRISTIAN W. WINTHORP, a citizen of the United States, and a resident of Fresno, county of Fresno, State 5 of California, have invented a new and useful Spring-Leaf Separator, of which the following is a specification.

My invention relates to an apparatus for separating the leaves of a leaf spring. 10 An object of my invention is to provide means wherewith the leaves of a leaf spring can be separated for the purpose of applying a lubricant thereto and for other purposes. The invention possesses other features of 15 advantage, some of which, with the foregoing, will be set forth in the following description of the preferred form of my invention which is illustrated in the drawings accompanying and forming part of the specification. It is to be understood that I do not limit myself to the showing made by the 20 said drawings and description, as I may adopt variations of the preferred form within the scope of my invention as set forth 25 in the claims.

Referring to the drawings:

Figure 1 is a side elevation of the spring leaf separator showing its application to a spring. 30

Fig. 2 is a top view of the separator.

Leaf springs are more efficient in absorbing shocks, and squeaking is avoided if the leaves are lubricated at intervals. The lubricant is best applied if the leaves are separated from each other, and it is an object 35 of this invention to provide means for accomplishing the separation of the leaves so that lubricant can be inserted therebetween.

My spring leaf separator comprises an L-shaped bar having a threaded arm 2 and an arm 3 at right angles to the threaded arm. Upon the threaded portion of the bar is mounted a stop or jaw 4 which may be adjusted longitudinally of the bar by turning 45 thereon.

The stop 4 extends outwardly from the bar and terminates in a blunt wedge 5, lying in a plane preferably substantially parallel to the arm 2 of the bar.

Upon the arm 3 of the bar, the jaw 7 is 50 pivotally mounted. On each side, the jaw 7 is formed with wedge shaped projections 8 having a portion 12, the plane of which is substantially parallel to the bottom surface 55 8a. It will be seen that a swinging move-

ment of the jaw 7 causes one or the other of the wedges 8 to approach the wedge shaped stop or jaw 4. The proportions and sizes of the parts are such that the wedges 8 lie in substantially the same plane with the 60 wedge shaped end 5 of the jaw 4. That end of the jaw 7 which is adapted to abut against the spring is preferably rounded in the form of a semi-circle, the center being the axis of the pivot upon which the jaw 65 swings.

Means are provided for swinging the jaw 7. An extension 14 of the jaw is provided with an aperture in which the shank 16 of the handle 18 is adapted to fit. The shank 70 16 of the handle is slidable longitudinally in the aperture in the jaw 7 and the shank is long, so that the position of the handle 18 with respect to the jaw may be suited to conditions surrounding the spring and the 75 handle may be turned without engaging other structural elements of the vehicle. The shank may be inserted into the aperture from above or below, depending upon surrounding obstacles. 80

Operation: It will be assumed that a leaf spring 21 is to be parted at A, Fig. 1, so that lubricant can be applied to the contacting surfaces. With the pivoted jaw in the position shown, the adjustable jaw 4 is 85 screwed upon the bar until the wedge 5 is as close as possible to the spring 21. By means of the handle 18, the jaw 7 is then turned in either direction to drive one of the wedges 8 between the two leaves which 90 it is desired to separate. The jaw is turned until the portion 12 is forced between the leaves, when there is no tendency to force out the wedge, and the lubricant is easily inserted. The wedge 5 is made blunt so that 95 immediately the wedge 8 is swung back out of the spring, the two leaves of the spring close with no tendency to hang on the wedge 5. The edges of the leaves abut against the rounded portion of the jaw 7 so that the 100 wedge 8 may be completely withdrawn from between the leaves.

Since the handle shank 16 can be inserted from either side of the jaw 7, and is slidable in its socket, and since the jaw 7 may be 105 turned in either direction, it is comparatively easy to avoid any reach rods or projecting parts of the vehicle which would otherwise interfere with the operation of the device. 110

I claim:

1. A spring leaf separator comprising a bar, an adjustable stop upon said bar, a wedge-shaped jaw pivotally mounted on said bar and a handle slidably arranged upon said pivoted jaw.
2. A spring leaf separator comprising a bar, an adjustable stop upon said bar, a wedge shaped jaw pivotally mounted on said bar and an L-shaped handle slidable in said pivotally mounted jaw and having one of its arms extending outwardly in a direction substantially parallel with said bar.
3. A spring leaf separator comprising a bar, a wedge-shaped stop adjustably mounted on said bar and having an end rounded concentric with the center of said pivot, wedge-shaped projections arranged one on either side of said rounded end, whereby turning said jaw upon said pivot causes one

of said wedge-shaped projections to approach said wedge-shaped stop, and means adjustably attached to said pivoted jaw for turning it upon its pivot.

4. A spring leaf separator comprising a bar, a wedge shaped stop adjustably mounted on said bar, a jaw pivotally mounted on said bar in a plane parallel thereto and having wedge shaped projections thereon whereby by a swinging movement in either direction causes one of said projections to approach said adjustable jaw, and means for swinging said pivoted jaw.

In testimony whereof, I have hereunto set my hand at Fresno, California, this 14th day of June, 1916.

CHRISTIAN W. WINTHER.

In presence of—

ARAM CHANNESIAN,
MINNIE SULLENGER.
